UNITED STATES PATENT OFFICE

2,386,594

CHARGE FORMING DEVICE FOR INTERNAL-
COMBUSTION ENGINESRussell Carkner Cone, Mine Centre, Ontario,
Canada, assignor of one-third to Walter G.
Hatcher, Mine Centre, Ontario, Canada

Application December 23, 1942, Serial No. 469,909

4 Claims. (Cl. 48—102)

My invention relates to charge forming attachments for internal combustion engines, having reference to a fuel oil vaporizing device for supplying oil to the engine intake.

In the art to which the invention relates a considerable wastage occurs in fuel consumption through improper breaking up of fuel oil particles whereby a portion of the fuel is not in condition to form a proper explosive charge. Various means of remedying this have been proposed, more particularly in preheating the charge and also in the provision of special vaporizing and atomizing attachments for dealing with the charge.

The present invention contemplates improvement in such devices by which the fuel oil is atomized and preheated and then subjected to baffling means to be discharged as a dry gas to the intake of the engine for forming the explosive charge.

One of the objects of the invention is accordingly to provide an improved charge forming attachment for internal combustion engines for effectively treating fuel oil and discharging the oil as a vaporized product to the engine intake.

A further object of the invention is to provide a fuel oil vaporizing attachment operating under pressure by which the fuel oil may be vaporized for delivery to the engine intake without addition of air in the vaporizing process.

A still further object of the invention is to provide in a fuel oil vaporizer of the character described improved controls for automatically maintaining the fuel feed supply to the engine in accordance with engine requirements.

Other features and advantages of the invention will become apparent by reference to the accompanying description taken in conjunction with the drawing.

In the drawing:

Fig. 1 is a side elevation of my improved attachment illustrated mounted on the engine intake manifold, certain parts of the attachment being shown broken away with parts in section for convenience in disclosing the various elements, and the fuel feed outlet being shown partly open to allow passage of fuel under pressure.

Having reference to the drawing 1 indicates the exhaust manifold of an internal combustion engine from which heat is derived for my attachment which is mounted in association therewith. The attachment is designed to receive fuel oil in liquid form and deliver the vaporized product to the engine intake manifold.

In the drawing, for convenience of illustration, the various fuel lines and valve housings have been shown relatively oversize.

A fuel pipe 2 for the attachment leads from a source of supply of fuel under pressure and delivers fuel through a feed line 3, said feed line

forming an integral part of a U pipe providing a bypass 4. The fuel flow is directed by a manually operable bypass valve 5. The source of supply and pressure means are not shown being common in the art.

A vaporizing chamber 6 includes an offset section 7 having an outlet 8 communicating with a diaphragm control housing 9 which in turn is connected by a pipe line 10 with the fuel inlet 3. Within the housing 9 is mounted a diaphragm 11 with stem 12 for actuation of a valve member 13 seated against an annular shoulder 14 at the inlet from feed line 3.

From the pipe line 10 a further feed or pipe line 15 connects to a valve chamber 16 communicating with the vaporizing chamber 6. The flow of fuel to the valve chamber is restricted to one way travel by a ball check valve 17. Within the chamber 16 is a needle valve stem 18 with suitable valve seat at 19. The needle valve stem is carried by a holder 21 threaded in the end of chamber 16 and in the holder the valve stem is mounted endwise movable to be adjusted by a knurled head 22.

The vaporizing chamber 6 provides an outlet conduit 23 leading from the rear end of the chamber and through which the vaporized fuel is discharged. Within the vaporizing chamber is mounted a series of heat conducting elements 24 receiving heat from the manifold 1 and over which the fuel is sprayed for initial vaporization. The elements 24 are of metal, preferably copper, of hollow construction and conical formation, said elements being inserted in suitable openings in the bottom of chamber 6. The rear portion of chamber 6 is provided with a double series of alternately arranged baffle plates 25 and 26 respectively attached to the bottom section of chamber 6 and the top section of said chamber, which latter forms the under side of conduit 23.

The baffle plates are somewhat diagonally disposed and terminate short of the opposing sections to leave a passage therethrough. Between the plates 25 are mounted a further series of heat conducting elements 27 in pairs, each pair being spaced by a plate 26. The elements 27 are of reduced size and number relative to elements 24 for maintaining the temperature of the vaporized fuel during passage through the baffle section of the vaporizer.

The vaporized fuel, after passage through the baffles, discharges by outlet conduit 23 to the offset portion 7 and then by way of an outlet pipe 28, valve chamber 29 and discharge pipe 30 to the engine intake manifold.

Passage of vaporized fuel through the valve chamber 29 is regulated by a valve stem 31 seated as at 32. The stem 31 is carried by a holder 33 threaded in chamber 29, the valve stem being

threaded to be endwise adjustable in the holder and actuated by a head 34.

Passage of fuel from the source of fuel supply to the vaporizing chamber is regulated by a diaphragm control member 11 opposing pressure of the incoming fuel and oppositely affected by pressure of vaporized fuel obtaining within the vaporizing chamber 6. A bypass is provided for automatic relief of overload on the engine. The bypass 4 includes a return outlet 35 leading to the source of fuel supply. Communication between bypass 4 and fuel feed line 3 is provided by a valve chamber 36 in which a valve 37 seats against an annular shoulder 38. The valve 37 is carried on a stem 39 endwise movable in a plug 40 mounted in a cap 41 which is threaded on the end of chamber 36. A spring 42 on the stem 39 normally holds the valve 37 seated against the shoulder 38 to close the outlet from the feed line 3.

The pressure in feed line 3 acts both against the valve 13 and the bypass valve 37. The valve stem 12 and diaphragm 11 are adapted to close the valve 13 by generated pressure in the vaporizer. Less pressure is required to open valve 13 when unopposed by generated pressure in the vaporizer than is required to open valve 37. When the demand of the engine falls below the working load for which it is set and sufficient pressure is generated in the vaporizer to overcome the pressure in feed line 3 the valve 13 will close and valve 37 will open.

Additionally to the foregoing there is provided a water jet 43 with pipe supply line 44 which would lead from a source of water supply, by which the humidity in the vaporizing chamber may be increased to give increased power to the charge.

In the operation of the device fuel delivered by fuel feed pipe 2 under pressure is bypassed by valve 5 when engine is first started, it being understood that in starting the engine fuel is supplied by the regular carburetor, the engine operating on gasoline until warmed up, when the valve 5 may be turned to direct fuel through the pipe 3 from where it passes by way of pipe 10 and feed line 15 to the valve chamber 16 from which it is sprayed in regulated quantities to the vaporizing chamber 6. In the chamber 6 the fuel is acted on by the hot shell plugs 24 and heated to a maximum safe temperature and then passed through the baffle section of the vaporizer. The vaporized fuel is then fed by the outlet 23 and offset 7 to the engine by way of outlet pipe 28, the flow of fuel to the engine being regulated by the valve member 31.

In event of overload the fuel is bypassed through the chamber 36 as hereinbefore described and a constant pressure maintained within the vaporizing chamber.

The device is designed to provide a steady regulated flow of fuel in the form of dry gas to the combustion chamber of the engine, designed to increase the power output of the engine and reduce oil dilution in the crank case. In this it is not required to mix air with the fuel until the fuel has become thoroughly vaporized.

While I have herein described a preferred embodiment of my invention it is obvious that changes in construction and arrangement of parts would be permissible within the spirit and scope of the invention as defined in the appended claims.

What I claim and wish to secure by Letters Patent is:

1. In a device of the character described a vaporizing chamber means for heating said chamber, a fuel feed line adapted for delivery of fuel under pressure, said feed line having a feed outlet and a bypass outlet, a valve for the bypass outlet, adjustable means for holding said valve closed with any desired pressure, a diaphragm valve housing having communication with the vaporizing chamber, a diaphragm in the housing responsive to pressure obtaining in the vaporizing chamber, a valve for the fuel feed outlet, a valve stem connecting said valve and diaphragm, and a further feed line connecting the fuel feed outlet and the vaporizing chamber.
2. In a device of the character described a vaporizing chamber means for heating said chamber, a fuel feed line adapted for delivery of fuel under pressure, said feed line having a feed outlet and a bypass outlet, said outlets providing valve seats, a valve for the bypass outlet, adjustable means for holding said valve seated with any desired pressure, a further fuel feed line connecting the fuel feed outlet and the vaporizing chamber, a diaphragm valve housing having communication with the vaporizing chamber, a diaphragm in said housing responsive to pressure obtaining in the vaporizing chamber, a valve for the fuel feed outlet, a valve stem connecting said valve and said diaphragm.
3. In a charge forming device for internal combustion engines, a vaporizing chamber, a series of heat conducting elements in the chamber, said chamber being located to receive heat from the engine exhaust manifold through the medium of said elements, a fuel feed line having a feed outlet and a bypass outlet, a further line connecting the fuel feed outlet and the vaporizing chamber, atomizing means in the discharge end of said further feed line, a diaphragm valve housing having communication with the vaporizing chamber, a diaphragm in the housing responsive to pressure obtaining in the vaporizing chamber, a valve for the fuel feed outlet, means connecting said valve and said diaphragm, a valve for the bypass outlet, and spring means holding the bypass valve closed with any desired pressure.
4. In a device of the character described a vaporizing chamber means for heating said chamber, a fuel feed line adapted for delivery of fuel under pressure, said feed line having a fuel feed outlet and a bypass for return of fuel to the source of supply, manually operable valve means for the feed line and bypass, a pipe communicating between the feed outlet and bypass, valve means for said pipe adjustable means for holding said valve closed with any desired pressure, a diaphragm housing communicating with the vaporizing chamber, a diaphragm in said housing responsive to pressure obtaining in the vaporizing chamber, a valve for the fuel feed outlet, a valve stem connecting said valve and said diaphragm, a further feed line connecting the fuel feed outlet and the vaporizing chamber, a series of heat conducting elements in the vaporizing chamber adapted to receive heat from the engine exhaust manifold, and atomizing means at the discharge end of said further feed line by which atomized fuel may be sprayed over the heat conducting elements.

RUSSELL CARKNER CONE.
